UNITED STATES PATENT OFFICE.

WILLIAM E. MAYER, OF CINCINNATI, OHIO.

FLASH-LIGHT APPARATUS.

1,333,030.

Specification of Letters Patent.

Patented Mar. 9, 1920.

Application filed February 20, 1918, Serial No. 218,199. Renewed October 13, 1919. Serial No. 330,523.

To all whom it may concern:

Be it known that I, WILLIAM E. MAYER, a citizen of the United States, residing at Cincinnati, in the county of Hamilton and State 5 of Ohio, have invented certain new and useful Improvements in Flash-Light Apparatus, of which the following is a specification, reference being had to the accompanying drawings.

10 This invention comprehends certain new and useful improvements in photographic supplies or accessories, and relates particularly to flashlights or lamps of the electric ignition type, such as is covered by Patent 15 No. 1,210,834, granted on January 2nd, 1917, to William B. Poynter and myself as joint owners.

The present invention relates more specifically to means for supplying one cartridge 20 at a time to the box or casing in which the ignition takes place to produce the flash, and it has for its primary object a very simple, practical and efficient device of this character, the parts of which may be very easily 25 manufactured and readily assembled and not liable to get out of order.

A further object of the invention is to provide an improved cartridge feeding slide so formed that a cartridge may be easily applied thereto and carried thereby into the main box or casing of the flashlight apparatus, means being provided whereby, when the slide is in its innermost operative position, the cartridge will be introduced positively into the electric circuit, so that when 30 the circuit is subsequently closed by the operator, the firing of the cartridge and the production of the desired flash will be insured.

40 A still further object of the invention is to provide an improved cartridge for the ignition powder, said cartridge being so formed that the supply of powder may be very easily renewed or replenished after each ignition and the cartridge being so correlated to the other parts of the device that it will be automatically opened to expose the powder as the slide is pushed into the casing.

The invention also has for one of its objects 50 an improved cartridge, the parts of which are so constructed and arranged that the fuse wire for igniting the charge may be easily renewed, and the cartridge being provided with a slide or cover which may be

easily slipped into place after the charge of 55 powder has been inserted within the cartridge, so that the cartridge may be easily handled and without danger of being accidentally fired.

The invention also has for one of its objects 60 an improved construction of cartridge designed particularly for use in connection with color photography, this form or embodiment of the invention, as it relates to the cartridge itself, being provided with two 65 slides or covers disposed in superimposed relation to each other, whereby one ingredient or combination of ingredients may be inserted in the cartridge and the lowermost slide then inserted in place, and subsequently the second 70 ingredient or combination of ingredients inserted within the cartridge above the lower slide or cover, and the uppermost cover then placed in position, whereby the danger which would otherwise be attendant 75 upon the mixing of these two ingredients or combinations of ingredients loosely in the cartridge will be obviated, both of these slides or covers being provided with means designed to coact with a shoulder formed in 80 the elongated case into which the cartridge holding slide is adapted to be inserted, so that both of the cartridge covers will be automatically moved into an inoperative position to expose the ignition powder as the 85 slide is inserted into the box of the apparatus.

And the invention also aims to generally improve and simplify devices of this character so as to render them more useful and 90 commercially desirable.

With these and other objects in view, as will more fully appear as the description proceeds, the invention consists in certain constructions, arrangements and combinations 95 of the parts that I shall hereinafter fully describe and claim.

For a full understanding of the invention, reference is to be had to the following description and accompanying drawing, in 100 which only so much of a photographic flashlight apparatus is illustrated to make the present invention clearly understandable, and which illustrates the preferred embodiment or embodiments of the device, it being understood, however, that the invention is not limited thereto, but that various 105 changes may be made in the construction, ar-

angement and proportions of the parts, without departing from the scope of the invention as claimed.

In the drawings,

- 5 Figure 1 is a horizontal sectional view through the box or casing of a photographic flashlight apparatus, such for example as is illustrated by the already issued patent above identified, the cartridge holding slide 10 being shown in top plan view and the case in which it slides being shown in section;

10 Fig. 2 is a top plan view of the slide itself, the cartridge being shown therein and in horizontal section;

- 15 Fig. 3 is a side view of the slide in position, the parts being shown in section;

Fig. 4 is a transverse sectional view on the line 4—4 of Fig. 3, looking in the direction of the darts;

- 20 Fig. 5 is a fragmentary top plan view of the inner end of the case in which the slide is adapted to be inserted;

Fig. 6 is a longitudinal sectional view of one form or embodiment of the cartridge 25 for the ignition powder;

Fig. 7 is an end view thereof; and

Fig. 8 is a fragmentary perspective view of the two slides or covers for this embodiment of cartridge.

- 30 Corresponding and like parts are referred to in the following description and designated in all of the views of the accompanying drawing by like reference characters.

Referring to the drawing, the numeral 1 designates the main box or casing of a photographic flashlight apparatus, and 2 designates an elongated case which is mounted therein and preferably formed of wood or fiber, said case being mounted upon the base 40 or bottom of the box 1 and being preferably rectangular and of inverted U-shape in cross section as best illustrated in Fig. 4.

3 designates my improved cartridge carrying slide. This slide may be formed of 45 any desired substance or material, preferably of a non-conducting character, and is provided at its inner end with a socket or cavity 4 into which the cartridge 5 is adapted to be placed and held, preferably, by frictional engagement with retaining springs 6 secured to the side and bottom walls of the cavity 4 as best illustrated in Figs. 2 and 3.

The cartridge 5 for the ignition powder is 55 preferably formed of fiber and is in the form of a rectangular box in the present embodiment of the invention, said cartridge being formed in its bottom with a preferably centrally disposed cavity 7 across which the fuse wire 8 is adapted to pass. This 60 fuse wire is inserted into the cartridge by being passed transversely through an opening 9 formed therein and extending from one side through the other, the ends of the wire, after the same has been inserted into 65 position, being preferably coiled one or more

times around binding screws 10. It will thus be understood that this fuse wire may be renewed after each ignition, the burned wire being easily pulled out from the cartridge by loosening the binding screws 10 and 70 a new wire being then inserted into place.

Secured to the opposite sides of the cartridge 5 are metallic plates 11, which contact with the binding screws 10 and extend longitudinally therefrom into contact with screws 75 12, which serve as contact points and which are designed to pass in between the curved free ends of contact members 13, which are arranged within the box 1 in laterally spaced relation to each other, the fixed ends of the 80 contact members 13 being electrically connected by leaves 14 to a switch box 15, in which is located a circuit closing device (not shown), designed to be operated by a bulb or the like, so that when the switch is actuated, the electric circuit will be closed 85 through the contact members and across the fuse wire 8 and ignite the charge.

The cartridge 5 further includes a sliding lid or cover 16, which is adapted to slip into 90 the body portion of the cartridge below the top thereof, so as to close the opening therein that is designed to receive and hold the ignition powder, whereby the filled cartridge may be safely handled. The lid or cover 95 16 is formed at one end with an upstanding lug 17 and this is designed to engage a shoulder 18, which depends from the top of the case 2, as best illustrated in Fig. 3, and it will thus be understood that as the slide 100 3 is inserted in place, the engagement of the lug 17 with the stop or shoulder 18 will hold the lid or cover stationary while the slide 3 moves on and inward to its fully operative position, the ignition powder 105 within the cartridge being thereby fully exposed ready for the circuit to be closed and the flash to be produced.

Preferably the inner end of the case 2 for the slide 3 is provided with a flap or shutter 19, hinged at its upper end upon a frame 20 of wire or the like, or otherwise so arranged that the shutter will normally close the inner end of the case 2, the inward movement of the slide 3 opening or raising 110 the shutter 19 as best illustrated in Fig. 3, it being thereby understood that when the slide is thereafter retracted and removed, this shutter will swing downward to its operative position and thereby prevent any 115 egress of smoke at this point. Preferably the shutter 19 is formed with recesses 21 for the passage of the contact members 13 (see Fig. 5).

If desired, the slide 3 may be provided at 125 its outer end and along one side edge thereof with a spring catch 22 having a shoulder 23 designed to engage a portion of the box 1 when the slide is in its innermost and operative position, although this is not indis- 130

pensable because the spring engagement of the contact members 13 with the contact points 12 will hold the slide in its innermost position and prevent any accidental detachment or disarrangement of the parts. Also, if desired, the slide 3 may be provided with a stop 24 in the form of a screw or the like designed to engage the outer side of the box 1 when the slide is in its innermost position, 10 so as to prevent it from being pushed in too far.

In that form or embodiment of the cartridge, which is illustrated in Figs. 6, 7 and 8, the cartridge, there designated 5', is designed particularly for use in connection with color photography and with that in view is provided with two superimposed lids or covers, designated 16' and 16'' respectively. Each of these lids or covers is 20 formed at one end with a lug for engagement with the stop or shoulder 18 hereinbefore referred to, and to allow the uppermost cover 16'' to be slipped into place after the lower lid or cover 16' has been 25 placed in position, the upstanding lug 17' of the lowermost cover 16' is cut away or recessed as best illustrated in Fig. 8. The lug of the uppermost cover 16'' is designated 17''. By providing a cartridge of this form 30 and construction of parts, it will be understood that one ingredient or combination of ingredients, to compose the ignition charge, may be poured into the cartridge and the lid or cover 16' then inserted in place, after 35 which, another ingredient or combination of ingredients may be poured into the body portion of the cartridge above and upon the cover 16' and the uppermost cover 16'' then slips into place. By these means, all danger 40 of handling the different chemicals or combination of chemicals will be obviated, the same being mixed after the cartridge has been inserted within the box 1, the two slides being automatically removed or detached 45 from the cartridge as the same is pushed inward.

From the foregoing description, in connection with the accompanying drawing, the operation of my improved photographic flashlight apparatus will be apparent. In the practical use of the device, after a cartridge has been filled with its ignition powder, it is slipped into the cavity 4 in one end of the slide 3 and the latter is inserted 55 into the box 1. As the slide is pushed inward, the upstanding lug on the lid or cover of the cartridge will be engaged by the shoulder 18 within the case 2 and the cartridge, with its ignition powder exposed, 60 will be moved inward to its fully operative position, with its contact points 12 engaging the contact members 13. Thereupon, by squeezing the bulb or otherwise closing the circuit by means of the devices within the 65 switch box 15, the charge will be ignited

and the flash produced, after which the slide is withdrawn and the cartridge taken out and refilled preparatory to a second operation.

In order that the slide 3 may operate with either of the two forms or embodiments of cartridge hereinbefore described, it is formed near its inner end and on its upper side with a longitudinally extending recess 25 to allow the lowermost lid or cover 16' 75 to move relatively backward as the slide is pushed in.

It will thus be seen that I have provided a very simple, practical and efficient cartridge feeding device, the parts of which 80 may be easily manufactured and readily assembled and not liable to get out of order.

Having thus fully described my invention, what I claim is:—

1. In a photographic flashlight apparatus, 85 a cartridge carrying member, a cartridge arranged to be carried thereby and provided with a lid, a case into which said member is adapted to be inserted, and means for automatically withdrawing said lid to expose the 90 contents of the cartridge upon the inward movement of the slide.

2. In a photographic flashlight apparatus, the combination of a cartridge designed to contain an ignition powder, means for moving 95 said cartridge into position, means for normally covering the powder, and means for automatically uncovering the powder as the cartridge is moved into position.

3. In a photographic flashlight apparatus, 100 the combination of a cartridge designed to contain a supply of ignition powder, a sliding cover for said powder mounted upon and included in the cartridge, said cover being formed with an upstanding lug, means for moving the cartridge into position, and a shoulder engageable with said lug upon the 105 said movement of the cartridge whereby to automatically uncover the powder.

4. In a photographic flashlight apparatus, 110 a cartridge carrying slide, a case in which said slide is adapted to be inserted, said case being provided with a lug, a cartridge adapted to be carried by said slide and provided with a cover having an upstanding 115 lug, and a shoulder carried by the case and engageable with said lug as and for the purpose set forth.

5. In a photographic flashlight apparatus, 120 a box or casing, spring contact members mounted therein, a slide adapted to be inserted into the box, a cartridge adapted to be carried into the box by and with the slide, said cartridge being provided at opposite sides with contact plates and contact points 125 at one end of said plates for engagement with the contact members, a fuse wire insertible within and adapted to extend transversely across the cartridge, binding screws for the ends of said wire, said screws con- 130

tacting with said plates, and means for removably holding the cartridge in operative relation to the slide.

6. In a photographic flashlight apparatus, a cartridge carrying slide provided at one end with a cavity adapted to receive a cartridge, and spring retaining members in said cavity designed to frictionally engage the cartridge and hold it securely, but detachably, in place.

7. In a photographic flashlight apparatus, a cartridge carrying slide, a longitudinally extending hollow casing through which said slide is movable longitudinally, the casing being open at its inner end to permit the projection of the slide through the open end of the casing, and a shutter operatively supported in conjunction with the inner end of the casing and normally closing the inner end of the casing upon the withdrawal of the slide but shiftable from its closing position upon the projection of the slide through the end of the casing, said shutter being constantly urged toward its closing position.

8. In a photographic flashlight apparatus, a cartridge formed with a cavity to receive ignition powder, and two superimposed covers for said cavity adapted to be slipped into the cartridge, each of said covers being formed at one end with an upstanding lug for the purpose specified, and one of said lugs being cut away to allow the passage of the other slide therethrough.

9. In a photographic flashlight apparatus, a cartridge formed with a cavity to receive

ignition powder, a plurality of superimposed covers for said cavity slidably mounted in the cartridge and spaced from each other, a slide upon which said cartridge is supported, a casing into which the slide is insertible, and means for causing the withdrawal of said covers as the slide is inserted in the casing.

10. In a photographic flashlight apparatus, a casing, a slide insertible into the casing and carrying a cartridge, a plurality of superimposed covers slidably mounted on the cartridge and normally disposed in spaced relation, and means for withdrawing said covers from the cartridge as the slide is inserted into the casing.

11. In a photographic flashlight apparatus, a casing, a slide insertible into the casing and having a cavity at one end, a cartridge disposed in said cavity, the cartridge having a cavity to receive ignition powder, a sliding cover mounted in the cartridge and adapted to be shifted from a position covering the cartridge to a position uncovering the cartridge, and coacting lugs on the sliding cover and the casing whereby the sliding cover is withdrawn as the slide is inserted into the casing.

In testimony whereof I hereunto affix my signature in the presence of two witnesses.

WILLIAM E. MAYER.
